WINDOW MOUNTING FOR STREAMLINED
VEHICLESEdward L. Helwig, Bristol, Pa., assignor to Röhm
& Haas Company, Philadelphia, Pa.

Application December 16, 1937, Serial No. 180,149

8 Claims. (Cl. 244—129)

This invention relates to a window and to the method of mounting the transparent material in the frame. It relates more particularly to windows for stream-lined vehicles, especially aircraft in which a smooth, continuous surface is highly desirable. It further relates to a method for mounting the transparent sheet material whereby an air-tight joint between the glass, frame and body of the vehicle is obtained. It also relates to the use of certain glass-clear, transparent, plastic materials in the manufacture of such windows.

In order for the pilot of an airplane to be able to see his surroundings, windows are necessary in the control cabin. Heretofore many of these have been made of glass or certain transparent plastics. Glass has the disadvantage that it cannot be easily shaped to conform with the stream-line contours of the body of the plane. The plastic materials can be so formed but up to the present there has been no satisfactory method of mounting the material in the frame so that both frame and transparent material form a continuous surface with the body of the airplane. It is well known that even small irregularities in the surface or protuberances greatly increase the resistance of the plane when moving at high speeds. Thus, in order to obtain the greatest efficiency from the power plant, every endeavor has been made to build the outer surfaces of the plane strictly according to the stream-line effect and to have as few protuberances as possible on that surface. When glass windows are employed, it is customary to bevel the edges from the outside and use a beveled retaining molding to hold the windows in place. This method has also been used to some extent with plastic windows. It is not very satisfactory, however, as the beveled panel is weakened at the mounting which is just the place where the maximum strength is desired. Furthermore, the beveled surfaces have a tendency to push the windows out of their moldings. This is particularly true with plastic windows. To overcome this latter objection, some manufacturers have milled a rectangular flange around the windows and used rectangular retaining moldings. This overcomes the latter objection but weakens the panels still more than beveling the edges.

Others in working with plastic windows have attempted to solve this problem by crimping the edges of the windows to accommodate a beveled retaining molding. This, however, makes the forming of curved windows very difficult as it greatly increases the complexity of the mold and

increases the likelihood of optical distortion. The windows with crimped edges, furthermore, have a tendency to slip out of their mountings just as the beveled ones do.

It is an object of this invention to provide a method whereby the windows, preferably of plastic material, can be mounted in the body of the airplane in such manner that the window and frame form a continuous stream-line surface with the body of the fuselage. It is a further object of this invention to provide a method of mounting the windows whereby an air-tight joint is obtained. This permits atmospheric pressure to be maintained within the cabin even when flying at very high altitudes. 15

These objects are accomplished by cementing to the inside surface of the transparent sheet lugs or buttons in such manner that about one-half of the button extends beyond the edge of the sheet. The sheet, of course, is first cut to the proper size so that it fits exactly in the opening cut in the fuselage and it is of such thickness that when put in place the outer edges of the sheet and the edges of the opening are exactly flush. Preferably the thickness of the sheet is exactly the same as that of the frame surrounding the opening in the fuselage as this simplifies the method of mounting. The sheets are placed in the opening, thus bringing the extending portion of the button in contact with the inner surface of the fuselage. A ring gasket, preferably of rubber, which has slots or holes cut in it to receive the buttons is then placed around the edge. Over this gasket is placed a metal strip or ring which is clamped down tight on the gasket by means of bolts extending through the body of the fuselage. The heads of these bolts are flat and countersunk in the body and are pulled up tight by means of nuts on the inside of the plane. 35

The invention may be more accurately described with reference to the accompanying drawing in which:—

Fig. 1 is a fragmentary plan view of the inside surface of a plastic sheet equipped with circular buttons. 45

Fig. 2 is an edge view of the same sheet.

Fig. 3 is fragmentary view of the mounting of the plastic sheet as viewed from the outside of the body, showing the mounting of two sheets of plastic in one opening.

Fig. 4 is a fragmentary cross section on line IV—IV of Fig. 3, and

Fig. 5 is a similar cross section on line V—V of Fig. 3.

Referring more specifically to the drawing the

plastic sheet 2 has buttons or lugs 3 cemented to the inside surface in such manner that about one-half of each button extends beyond the edge of the sheet. These sheets may be square, rectangular, circular, elliptical or any other desired shape and may be flat or shaped to conform with the stream-lining of the body. In the drawing they are shown square and flat for convenience. The buttons may be any desired shape but circular ones are most convenient.

Any suitable plastic may be used for the manufacture of the windows and any suitable material may also be used for the lugs. The preferred material for both is a polymer of methyl methacrylate. When such material is used, the lugs may be attached to the sheet by moistening the surfaces of each with some monomeric methyl methacrylate, placing the lugs in position and holding them while the monomer is polymerized. In this manner the lug becomes an integral part of the sheet and is not merely joined to it by means of an adhesive.

In assembling the window the plastic sheet is placed in the opening cut in the body 4 of the fuselage so that the surface of the lug comes in contact with the inner surface of the body. A rubber gasket 5 in which holes are cut corresponding to the lugs is then placed around the edge of the sheet. This gasket is pressed tightly against both body and sheet and is held in place by a metal ring 6 which is drawn up tight by means of bolts 8 which pass through the gasket and the body of the fuselage. When the window is so large that more than one sheet of plastic is required, the two sheets may be joined as shown particularly in Fig. 5. In this case a metal strip 9 is inserted between the adjacent edges of the sheets. The bolts 10 which hold the assembly in place pass through this strip, which is fastened at its ends by any suitable means to the body of the fuselage, and through the strip 9 and when the nuts are taken up an air-tight joint is made due to the sealing effect of the rubber gasket.

This method of making the windows has many advantages over the methods heretofore used. The outer surface of the windows conforms perfectly with the stream-lining of the body and there are no projections of any kind to increase the friction in the air. The plastic material may be made to withstand any differences in pressure between the inside and the outside by properly choosing the thickness of the sheet. The lugs when properly attached to the sheet are capable of withstanding any pressure encountered in flying. The size of the sheets and lugs and the maximum of pressure difference will determine the number of lugs required for any given window.

This method of mounting the transparent sheets in the fuselage of airplanes is applicable to all transparent material such as glass, Celluloid, cellulose acetate, vinyl resins, methacrylic resins, etc. The preferred material, however, is polymeric methyl methacrylate or a joint polymer containing principally methyl methacrylate. This material is sufficiently strong for all purposes, it is not affected by the weather, is not easily shattered and remains clear and transparent indefinitely.

70 I claim:

1. A window adapted for use in vehicles having stream-lined bodies comprising a sheet of transparent material fitting flush with the outer surface of the body, lugs on the inner surface of said sheet adapted to contact the inner surface

of the body and clamping means adapted to hold said transparent sheet in place.

2. A window adapted for use in airplanes comprising a sheet of transparent material fitting flush with the outer surface of the fuselage, lugs 5 on the inner surface of said sheet adapted to contact the inner surface of the fuselage and clamping means adapted to hold said transparent sheet in place.

3. A window adapted for use in airplanes comprising a sheet of transparent material fitting flush with the outer surface of the fuselage and conforming with the stream-lining thereof, lugs on the inner surface of said sheet adapted to contact the inner surface of the fuselage and 15 clamping means adapted to hold said transparent sheet in place.

4. A window adapted for use in airplanes comprising a sheet of transparent material fitting flush with the outer surface of the fuselage and 20 conforming with the stream-lining thereof, lugs on the inner surface of said sheet adapted to contact the inner surface of the fuselage and clamping means including a metal frame and bolts passing through the frame and the body 25 of the fuselage and a gasket between said frame and the body adapted to press the transparent sheet in place and form an air-tight point.

5. A window adapted for use in airplanes comprising a sheet of transparent plastic material 30 fitting flush with the outer surface of the fuselage and conforming with the streamlining thereof, lugs on the inner surface of said sheet adapted to contact the inner surface of the fuselage and clamping means adapted to hold said transparent 35 plastic sheet in place.

6. A window adapted for use in airplanes comprising a transparent sheet of polymeric methyl methacrylate fitting flush with the outer surface of the fuselage and conforming with the stream-lining thereof, lugs of polymeric methyl methacrylate joined to the inner surface of said sheet and adapted to contact the inner surface of the fuselage, clamping means including a metal frame and bolts passing through said frame and said 45 fuselage and a rubber gasket having holes to receive said lugs and adapted to press said sheet in place and form an air-tight joint.

7. A window adapted for use in airplanes comprising more than one transparent sheet of plastic 50 material, said sheets fitting flush with the outside surface of the fuselage and conforming with the stream-lining thereof, lugs attached to the inside surface of said sheets along all edges, said lugs adapted to contact the inside surface 55 of the fuselage, a metal strip lying between adjacent edges of said sheets and contacting the lugs on those edges, and being flush with the outer surface, clamping means including a peripheral frame and a cross member corresponding 60 in position with said metal strip and bolts arranged to clamp said frame to the fuselage and said strip to the cross member, a rubber gasket lying between said frame and the plastic sheet and between said metal strip and the cross member 65 and adapted to press said plastic sheets into position and form an air-tight joint.

8. A window adapted for use in airplanes comprising more than one transparent sheet of methyl methacrylate, said sheets fitting flush 70 with the outside surface of the fuselage and conforming with the stream-lining thereof, lugs attached to the inside surface of said sheets along all edges, said lugs adapted to contact the inside surface of the fuselage, a metal strip lying 75

between adjacent edges of said sheets and contacting the lugs on those edges, and being flush with the outer surface, clamping means including a peripheral frame and a cross member corresponding in position with said metal strip and bolts arranged to clamp said frame to the fuselage and said strip to the cross member, a rubber

gasket lying between said frame and the methyl methacrylate sheets and between said metal strip and the cross member and adapted to press said methyl methacrylate sheets into position and form an air-tight joint.
